(57) **CLAIM**

(21) Appl. No.: **29/234,740**

The ornamental design for the earphone, as shown and described.

(22) Filed: **Jul. 22, 2005**

DESCRIPTION

(30) **Foreign Application Priority Data**

Jan. 26, 2005 (KR) 30-2005-0002626

FIG. 1 is a perspective view of the earphone showing our design;

(51) **LOC (8) Cl.** **14-01**

FIG. 2 is a front view thereof;

(52) **U.S. Cl.** **D14/223**

FIG. 3 is a rear view thereof;

(58) **Field of Classification Search** D14/205,
D14/206, 233, 192, 188; D24/174; 379/430,
379/433; 181/129, 130; 381/374, 376, 377,
381/378, 379, 381

FIG. 4 is a left side view thereof;

See application file for complete search history.

FIG. 5 is a right side view thereof;

FIG. 6 is a top plan view thereof;

FIG. 7 is a bottom plan view thereof; and,

FIG. 8 is a side view thereof shown with an environment for use.

The broken line is understood to be for illustrative purposes only and forms no part of the claimed design.
